UNITED STATES PATENT OFFICE.

HUBERT SCHAFFERT, OF HALLE-ON-THE-SAALE, GERMANY.

FURNACE-CHARGING MECHANISM.

Application filed June 1, 1925, Serial No. 34,150, and in Germany February 26, 1926.

This invention relates to charging devices for roasting, heating, hardening or cementation drums.

In the known devices described in German Patent No. 391,547, there is closely fitted on to one end of the heating drum, built in and rotating in the hardening furnace, a charging funnel and on the other end a quenching chamber.

10 It is of great importance that the closure, especially of the charging device, is absolutely gas-tight as otherwise noxious gas can escape from the drum and also the process itself is adversely affected.

15 According to the present invention, a charging device is used which renders possible uniform and intermittent charging of the heating drum through an absolutely gas-tight closure, which has hitherto not been achieved in the known charging devices wherein each time the closing valve was opened for filling, gas could naturally escape or enter. The charging device according to the invention is clearly illustrated in the accompanying drawings in which,

20 Fig. 1 is a view in longitudinal section of the entire device;

25 Fig. 2 is a transverse sectional view of the charging device taken on the line 2—2 of Fig. 1, and

30 Fig. 3 is a transverse sectional view of the operating means for the charging device taken on the line 3—3 of Fig. 1 looking in the direction of the arrows.

35 The charging device consists essentially of a valve 1 which is mounted rotatably in the chamber 2 of the inlet guide 5 on the shaft 3 and which works similarly to the ordinary bucket wheel charging devices. It

40 is provided with a filling aperture 6 and a discharge aperture which are so arranged

relatively to one another that one aperture is always sealed gas-tight by the walls of the chamber 2 when the other is in the open position and vice versa.

45 Thus when the interior of the rotatable valve has been filled with the desired quantity of charge, the drum 1 can be turned through 90° by means of the hand-lever 4 whereby the discharge aperture 7 is brought 50 into position over the delivery tube 8 whilst at the same time the chamber wall 2 of the inlet guide is sealed gas-tight.

55 In order to ensure a uniform charging, the driving wheel *c* of the roasting hardening or cementation drum *b* is furnished with a projection 9 which turns the rotatable slide-valve 1 into the discharge position on each rotation of the drum and immediately releases it whereon the valve is returned to 60 its original position by means of a spring 10 suitably located. In this way it is ensured that the charge is supplied to the drum at uniform intervals and always when, in the charging position, a complete thread 65 of the conveying screw has just become free.

I claim:

70 In apparatus of the class described a rotatable drum, charging means for the drum including a hollow cylindrical valve provided with spaced inlet and discharge openings, and a casing for said valve including an inlet guide, said valve having a radial arm and said drum being provided with a tappet member to engage said arm and thereby cause said drum at each rotation thereof to partly turn said valve, and a spring to return said valve to normal position.

75 In testimony whereof I have affixed my signature.

HUBERT SCHAFFERT.
